UNITED STATES PATENT OFFICE.

JOSEF SEMERAK, OF NIEDERLÖSSNITZ, GERMANY.

MASSAGE APPARATUS.

SPECIFICATION forming part of Letters Patent No. 634,590, dated October 10, 1899.

Application filed August 30, 1898. Serial No. 689,849. (No model.)

To all whom it may concern:

Be it known that I, JOSEF SEMERAK, a subject of the Emperor of Austria-Hungary, and a resident of Niederlössnitz, near Dresden, 5 Kingdom of Saxony, German Empire, have invented certain new and useful Improvements in a Combined Massage and Beating Apparatus, of which the following is a specification.

This invention relates to a combined massage and beating apparatus comprising a roller adapted to be rotated under a desired pressure over the body and to thereby raise and release caoutchouc or other elastic hammers carried on spring tongues or stems, so that in operating the apparatus said hammers are caused to beat alternately upon the part of the body under massage treatment.

In the accompanying drawings, Figures 1 and 2 are respectively a longitudinal section and a plan of the apparatus of the invention with cover removed; and Figs. 3 and 4 are similar views, but with a modified means for regulating the heaviness of blow of the hammers.

b is a casing partly open underneath and formed of the two upright sides w and sheet-metal plate-cover z, which takes over the sides and incloses them in the manner and to 30 the extent shown in the drawings.

z are bolts connecting the sides w.

The casing is of a size and shape suitable for holding in the hand, or it can be provided with a special handle.

The roller is formed of small wheels a, firmly connected together, carried on a spindle mounted in the sides of the casing and provided with suitable grooved rims for the reception of india-rubber tires. The roller 40 thus formed projects out of the bottom of the casing convenient for running it over the body for massage purpose.

a' are pins, in any suitable number, fixed in different positions between and rigidly 45 staying the wheels of the roller. Opposite these pins are located spring-tongues c, to each of which, near its front end, is fixed a hammer d, preferably of or covered with elastic material. Said hammers when in 50 their bottom position also project out of the bottom of the casing.

Of course, if preferred, the roller may have the form of a single wheel instead of several,

with only one lifting-pin a' and hammer instead of a number of the same. Further, 55 each hammer may be operated by either one or more lifting-pins, so as to give one or more blows from a hammer in the course of a revolution of the roller.

When the apparatus is run upon the roller 60 or wheels a in the direction shown by the arrows, Fig. 1, the pins a' successively impinge against the hammer-tongues c and lift them with the corresponding hammers until the pins pass out of range of the hammer-tongues, 65 whereupon the hammers fall and give elastic blows upon the body.

For regulating the heaviness of blow of the hammers the hammer-tongues c, Figs. 1 and 2, are attached to a cross-bar d', adapted to 70 swing by end pins d² on bearings in the sides of the casing and provided with an arm d³, having a threaded orifice for the engagement of a set-screw e, adjustable in a slot e' in the side of the casing concentric to the pins d². 75 According as the set-screw is adjusted in the slot e', the bar d', through its arm d³, is also adjusted to cause the hammer-tongues to turn and project the hammer-heads more or less out of the casing, and thus increase the 80 strength of or weaken their blows. The same end may be attained by other means—for instance, as shown in Figs. 3 and 4, where a cross-bar e² is arranged to slide at the ends in slots f, provided in the sides w of the casing, and thus guide the bar over the hammer-tongues c, which when lifted by the pins a' bear against said bar, and thus have their working length limited. Said bar e² is provided with a screw-threaded aperture, and its 90 adjustment is effected from the outside of the casing by means of the hand-screw h, working through said aperture and secured against displacement from its proper position by a collar k on the same, which is held between the cross-bar d' and bracket l, attached to said spring-tongue carrying-bar d'.

What I claim is—

1. A hand massage and beating apparatus comprising a frame or casing, a wheel journaled therein adapted to contact with and be rotated by the surface of the body as the frame or casing is moved over the same, and a spring-hammer arranged to be operated by said wheel, substantially as described. 100

2. A massage and beating apparatus of the

kind referred to, comprising a casing *b* open at bottom, a series of wheels *a* adapted to turn and projecting from said casing, a number of spring-hammer tongues *c*, furnished 5 with soft elastic hammer-heads *d* and lifting-pins *a'* arranged between the wheels for lifting and releasing the hammers successively when the apparatus is run over the body under pressure.

10 3. A massage and beating apparatus comprising a casing, a plurality of rollers therein, pins or projections carried by said rollers, a

plurality of spring-tongues carried in the casing and overlapping the pins, hammer-heads 15 carried by said tongues and means for adjusting said tongues toward and from the rollers, substantially as described.

In witness whereof I have hereunto set my hand in presence of two witnesses.

JOSEF SEMERAK.
